(57) **CLAIM**

The ornamental design for a combined business card with bar code, laser punched holes and radio frequency IC, as shown and described.

DESCRIPTION

FIG. 1 is a perspective view of a combined business card with bar code and laser punched holes and radio frequency IC showing my new design;

FIG. 2 is a front elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a rear elevational view thereof;

FIG. 8 is a perspective view of FIG. 7 thereof;

FIG. 9 is an enlarged cross-sectional view taken along lines 9—9 of FIG. 2 thereof;

FIG. 10 is an enlarged cross-sectional view taken along lines 10—10 of FIG. 2 thereof;

FIG. 11 is an enlarged fragmentary cross-sectional view taken along lines 11—11 of FIG. 7 thereof;

FIG. 12 is a second embodiment of rear elevation view FIG. 7 thereof, it being understood that the undisclosed front, right-side, left-side, top and bottom views are the same as in FIGS. 2—6; and,

FIG. 13 is a perspective view of FIG. 12.

The broken lines showing letterings and numerals in FIG. 1 and FIG. 2 are for illustrative purposes only and form no part of the claimed design.
